UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

ASSOCIATING AND COLLECTING MECHANISM.

1,238,613.

Specification of Letters Patent. Patented Aug. 28, 1917.

Application filed October 5, 1908, Serial No. 456,150. Renewed February 9, 1916. Serial No. 77,299.

To all whom it may concern:

Be it known that I, HENRY A. WISE WOOD, a citizen of the United States, residing at New York, in the county of New York, and State of New York, have invented a new and useful Associating and Collecting Mechanism, of which the following is a specification.

This invention relates to a mechanism for associating and collecting the product of a printing press or printing presses. The particular objects thereof are to provide a construction for this purpose whereby the sheets or web can be stapled while on the run without reducing their speed and to provide efficient mechanism for stapling the same transversely. The invention also comprises in this construction a reciprocating wire stapling device combined with the collecting mechanism, means for combining with the rest of the mechanism, a device whereby a cover may be added to the assembled and finished product, and various improvements in the construction and operation of machines of this character. Further objects and advantages of the invention appear hereinafter.

Reference is to be had to the accompanying two sheets of drawings in which—
30 Figure 1 is a sectional elevation of one form of the invention showing an arrangement of the stapling device in connection with a printing press and collecting mechanism.

35 Fig. 2 is a plan of the stapling mechanism shown in Fig. 1.

Fig. 3 is a view similar to Fig. 1 on an enlarged scale showing the stapling mechanism; and

40 Fig. 4 is a sectional elevation showing how the stapling device can be used in connection with associated webs.

The wire stapling device is adapted to permanently secure or fasten the assembled product, obtained either by associating webs or collecting sheets.

Referring now to the drawings it will be seen that on a short shaft 22 is fulcrumed a vibratory lever or arm 23, which arm is actuated to insert the staples, as hereinafter described.

Extending up from the left hand portion of this arm 23 are brackets or arms 24, in which is journaled a shaft 25.

Also mounted upon the shaft 25, and between the bearings 24 is a mallet or striking piece 33, which may be securely fastened to the shaft 25. On the end of the vibrating arm or lever 23 is formed a stapling head 34.

60 The striking head 34 has an extending reservoir 42, in which the staples may be placed, or to which they may be fed.

One way in which a stapling device can be combined with a collecting mechanism, is shown and also means by which a cover may be combined with the finished product.

In the drawings, it will be seen that the collecting mechanism is shown as taking its supply from a printing mechanism; but broadly, any collecting mechanism may be used, no matter whether the material is led directly thereto, as in the form of a web from the press, or whether sheets are fed to the same.

75 In this specific device 70 represents a web-roll from which the web 71 is led.

From the web-roll, the web passes around a roller 72, then around the impression cylinder 74, then around the impression cylinder 75.

Coacting with the impression cylinder 74 is the first type cylinder 73, and coacting with the second impression cylinder 75 is the type cylinder 76, which type cylinders 85 can be inked by any suitable inking apparatus as I, which it is not necessary here to show or describe at length.

The type-cylinders preferably are made of a circumference so as to receive four plates around the same, so that a variety of products can be produced, as hereinafter described.

Thus, for example, if the first and second plates of the type cylinders are different, and the third and fourth plates 95 are like the first and second, the first sheet may be associated with the second, and the third with the fourth, and two distinct double-sheet products may be produced, which are duplicates; or if two distinct and unlike 100 products are to be run, all the plates would differ, and the first complete product would

not be like the second. Or again, if it is desired to produce a complete quadruple-sheet product, then all the plates would be different, but all the four sheets would be collected, as hereafter described.

Thus, it will be seen that a printing couple which has four plates arranged circumferentially on the type cylinders is capable of producing a product, which may be cut and collected into a number of different products.

From the last impression cylinder 75, the web 71 is led between the cutting cylinders 77 and 79, which are made one-half the size of the type cylinders, and the upper cylinder 79 of which, has two knives as 80, and the lower cylinder 77 of which has two recesses 78, whereby the web will be cut into four sheets for the length of one circumference of each type-cylinder.

The knives 80 do not completely sever the sheet from the web, but simply perforate the web.

From the cutting cylinders, the web is carried over guides 82, and is led in between the bite of the continually running tapes 83 and 86. The tapes 83 are shown as mounted upon the tape pulleys 84 and 85, and tapes are mounted upon tape-pulleys 87, 88, 89, 90, 91, 92, 93 and 94, and these tapes are run at a faster speed than the peripheral speed of the cutting cylinders.

Arranged beyond the tape pulleys 85 and 87 is the collecting cylinder 97, and the nipping or biting cylinder 81, which may be also used as a collecting cylinder in some cases, as hereafter described.

The web is directed from the tapes 83 and 86 between these cylinders 81 and 97 by means of suitable guides 950.

Arranged in the collecting cylinder 97 are rubber pads 98 which are arranged preferably opposite, and also through these rubber pads may be inserted impaling pins 99. Impaling pins as 95 may be also inserted into the nipping cylinder 81. All the impaling pins are removable, and are used only as desired.

Coacting with the collecting cylinder 97 is a set of stripper fingers 100, which may be operated by any of the usual means to strip the collected product from the collecting cylinder; and a similar set of fingers 96 is arranged to coact with the cylinder 81, 55 and to strip the product from their cylinder, and deliver the same on to the strippers 100.

It will be seen that the tapes 86 are led around the nipping cylinder 81 so that the 60 tapes are clear of the same.

From the cutting cylinders 77 and 79, the web is carried between the tapes 83 and 86, until the end of the same comes in between the nipping cylinder 81 and the collecting 65 cylinder 97, when one of the rubber pads 98

seizing the end of the web, will tear the sheet from the web on the line of the perforations, which have been made by the cylinders 77 and 79, and this will leave the leading end of the web in the bite of the tapes 83 and 86, so that the sheets will be nicely severed from the web.

Coacting with the cylinder 97 is a set of tapes 101, which tapes are led around tape-pulleys 102 and 103, as shown, and coacting with the tapes 101 is a set of tapes 104 which tapes 104 run around tape-pulleys 105, 106, 107, 108 and 109, and drop-roller 110, which may be mounted in suitable arms 111.

By these tapes, a sheet may be fed to the 80 collecting cylinder to form either a supplement or a cover, as hereafter described.

The collected product passes from the strippers 100 in the grasp of the tapes 86 and 104, in through a stapling device.

A plurality of stapling devices are used, and instead of being mounted stationary in the frame, are mounted so as to reciprocate backward and forward as by being mounted on a traveling carriage, and all these 90 stapling devices are operated from the common shaft 22.

This shaft 22 has on the end thereof an arm 141, which carries a roller 136. The arm 141 is normally kept in its depressed 95 position by means of a compression spring 138, which is arranged between the arm 141 and an arm 137.

139 and 140 represent two transverse beams upon which guides 154 are arranged, 100 and on these guides, the moving carriage hereafter referred to, is mounted.

The stapling devices are operated from a pivoted arm 143, which has an extending arm 144, to which is connected an arm 145, 105 which has at the end thereof, a yoke 149, which yoke is kept normally in its highest position by means of a spring 146.

147 represents a cam mounted on a shaft 148, which the yoke 149 engages, and this cam has a projection 151. Arranged on the yoke is a roller 150, which bears on the face of the cam. By this means, the arm 143 will be raised at the proper time to operate the 110 stapling devices.

It will be seen that the roller 136 runs on the arm 143, and the cam 147 is so timed that when a relatively stationary relation is effected between the moving stapling devices and the moving assembled product, the 120 arm 144 will be pulled down, and thus the stapling devices will be operated.

The stapling devices are mounted in a carriage 152, which has rollers 153, which run upon guides 154.

The carriage 152 is given a forward and backward movement from a continuously rotating shaft 155, which carries a crank-arm or disk 156, with which is connected a connection 157, which has a rack 158 formed 130

on the upper end thereof, and this rack is fitted in a suitable guide 159.

This rack 159 engages a pinion 160, which is mounted upon a shaft 163, which shaft 5 163 carries gears 161, which engage racks 162 secured to the moving carriage 152, and preferably two gears 161 and two racks 162 are used.

By this means, it will be seen that the carriage 10 is moved forward and backward, as the shaft 155 revolves, and the parts are so timed that when the relation between the moving assembled product and the stapling device is substantially stationary, the stapling 15 device is caused to work from its cam, and thereby a transverse line of staples is inserted in the assembled product.

From the stapling device, the sheets are led out between the tapes 104 and 86 on a 20 suitable receiving table 1661 and come against a stop 1662, and then the assembled and stapled product is tucked between the folding rollers 164 and 165 by means of the tucker-blade 166, and the once folded, assembled, and stapled product may be delivered as by means of a fly 167 on a receiving table 168.

By this device, it will be seen that the collected product, before specifically described, either with a supplement or cover, 30 can have a transverse row of staples inserted therein, without the assembled product being stopped, and that it can be nicely folded upon the line of the staples.

35 Of course, instead of using a single web 71, another web may be led in as 710, and associated with the web 71 at the roller 720, or the web 71 could be slit, and its portions laterally associated to form a multiple web.

In this device, in which the staples are inserted transversely, and in which the product is folded transversely, it will be seen that the reservoirs 42 and their plungers are 45 turned at right angles to the position in which they would be placed if the staples were inserted in the longitudinal line, and for the reason that the staples should be placed so as to be in line with the fold.

50 As before stated, supplements or covers can be fed in between the tapes 101 and 104, and the covers or supplements may be fed from a suitable feed-table as 130, and are indicated by the letter C.

55 A suitable check device as 131 may be arranged upon a shaft 133, and may have a nose 132, and this device may be so arranged that it will only be possible to feed the cover or supplement in at the proper time.

The roll 110 mounted in the arms 111 may be also arranged, if so desired, to act as the usual drop-roll, to seize and forward the sheet at the proper time.

60 The gearing for the stapling device can be

operated at the proper time depending upon the number of assembled products that come from the collecting mechanism.

The cylinder 97 is driven turn for turn with the cutting cylinders, but is made about 70 one-fourth in diameter larger than the cutting cylinders; and by this means, will have the peripheral speed necessary for pulling the sheets from the end of the web, and all the tapes are preferably run at the same 75 speed as the peripheral speed of the collecting cylinder 97.

The nipping cylinder 81 is preferably made one-half the diameter of the collecting cylinder 97, and arranged to turn at the same 80 peripheral speed, or two turns for one of the collecting cylinder 97.

All these mechanisms and gearings are well understood and known in connection with web-presses and folding machines, and 85 it is not necessary to go into detail to describe the same, to give a skilled mechanic a full idea of this invention.

Suppose now, that it is desired to run 90 single sheets through the press. Then all the impaling-pins are removed from the cylinders 97 and 81, the stapling device is arranged so as to be inoperative, and the sheets will be pulled from the web, and given one fold, and delivered, as desired, the fly, of 95 course, being properly timed, and thus four four-page papers, once folded, will be delivered for each revolution of the type-cylinders, the stapling device, of course, being rendered inoperative during this operation. 100

Suppose now, in the second case, it is desired to collect two sheets, so as to form an eight-page product, and to deliver for each revolution of the type-cylinders two similar 105 eight page products, or two different eight-page products, depending upon the arrangement of plates used upon the type-cylinders.

In this case, the impaling-pins 95 are inserted in the small collecting cylinder 81, 110 and the strippers 96 are set to operate at every second revolution of the cylinder 81.

Then the first sheet fed in between the cylinders 97 and 81 will be carried up around the cylinder 81, and the next following sheet 115 will be collected with the first sheet, and then the two sheets will be stripped from the cylinder 81 by the strippers 96, and will be carried forward between the tapes 86 and 104 through the stapling mechanism, 120 and will be stapled, and thereafter delivered as desired.

Suppose now, in the third case, it is desired to collect all four sheets printed by one revolution of the type-cylinders. Then 125 the impaling pins 99 would be placed in the collecting cylinder 97, and the impaling pins 95 would be left in the nipping cylinder 81, and the strippers 96 would be set to operate as hereafter described, and the strippers 100 130

would be timed to operate once for each two revolutions of the cylinder 97.

Then the first two sheets would be laid upon the collecting cylinder 97, and the succeeding sheet would be collected with the first sheet, and the two would then be taken by the upper cylinder 81, and the fourth sheet would then be connected on the impaling pins 99, with the second sheet taken upon the cylinder 97, and then when the forward edges of all four sheets come together, the four-sheet product thus collected by the two collecting cylinders would be directed forward by the strippers 100 and 96 into the tapes 86 and 104.

From the strippers 100, the collected product will be carried on, stapled, folded and delivered.

By this operation, it will be seen that a sixteen-page paper will be formed, bound together and delivered once folded for each revolution of the type-cylinders.

Thus, by the printing and collecting and stapling mechanism before described, I can produce either single sheet, collected double sheet or collected quadruple sheet products.

In some cases, it is desired to add a cover or a supplement to these products, and this can be nicely done by feeding either the cover or supplement from the feed-board C, the stop 132 and the drop-roll 110 being timed so as to lead the supplement or cover in at the proper time.

In the first case, if it is desired to lay covers on the single sheet product, two covers will be fed in for each revolution of the collecting cylinder 97, the impaling pins 99 being used in this case, and will be carried up by the impaling pins 99 and collected under the single sheets.

From the collecting cylinder, the cover and single sheet will be stapled, folded and delivered, as before described.

When it is desired to put a cover on the eight-page product, only one cover is fed in for each revolution of the collecting cylinder 97, and when it is desired to put a cover upon the sixteen page collected product, one cover is fed in for each two revolutions of the collecting cylinder.

Of course, this fed-in sheet, instead of being considered as a cover, can be considered as a supplement, and under some conditions, can be used as an insert.

This supplement or cover may, of course, be a full width or a half width sheet, so that a half cover can be added or only a one page supplement.

By this means, it will be seen that a great variety of products can be obtained, with comparatively simple mechanisms, and that by momentarily stopping the collected product one or more times the same can be permanently and nicely bound together.

Thus, this press can be arranged to sup-

ply either four four-page papers, two eight-page papers, either similar or different, or one sixteen page paper for each revolution of the type-cylinders; or, if a half-width cover is added, it can produce the above with a two-page cover; or if a full width cover is added, it can produce the above with a double page cover.

Of course, in feeding in the supplement or cover of one page width to constitute two pages, a wide margin is left, which can be nicely stapled to the remaining sheet or sheets, and can be nicely folded.

Thus, it will be seen that this device constitutes an improved collecting mechanism, means for continuously moving the assembled product, and a stapling device adapted to insert staples to permanently bind the collected product together, while the same is moving, so as to give a transverse line of staples, and of a folder adapted to give the collected and bound product a fold on the line of the staples. This will give a press which is adapted for a great variety of pamphlet and nice work.

In the device which I have just described, it will be seen that the momentary stationary relation between the stapling device and the assembled product is effected by moving the stapling device backward and forward, and so proportioning the parts that at one time the stapling device will move in unison with the assembled product, and when this stationary relation between the moving assembled product and the moving stapling device is thus effected, inserting the staple or staples.

The associated webs can be stapled and fastened together while they are on the run by using the moving stapling device and this construction is shown in Fig. 4, the parts otherwise being the same as before described, and this moving stapling device simply being placed in the line of the associated webs that are to form the pamphlet, between the rollers 189 and 175.

Thus the associated webs can be stapled while they are on the run.

In this last device the staples will be inserted in a transverse line, and it is preferred with this device to use a transverse folder to act on the product after the same has been cut off, and this may consist of a pair of the usual ordinary transverse cutting and folding devices as 602 and 603.

From the last impression cylinder, the cover e is led around a roll 214 to a roll 215; and interposed between the rollers 214 and 215 is a pasting device, which may consist of a suitable paste-box 210, which has a suitable pasting roller 211, which deposits paste upon the lining-roller 212; between which rollers 212 and 213, the web e is led.

It is preferred in using this arrangement to provide the pasting-roller 212 with a

knife so as to deposit a transverse line of paste on the cover e^1 .

Thus, it will be seen, that sheets can be collected as desired from one web, and 5 stapled and folded while on the run; that webs slit from one web, or produced from two or more machines can be associated, and 10 stapled and folded while on the run; that covers or supplements can be inserted with the collected sheets, the said covers or 15 supplements being not necessarily in dimensions an equal division of the circumference of the type-cylinders; and they can be bound with the product; and that all the pages of a pamphlet can be associated in web, and 20 stapled, and thereafter a cover can be pasted on the stapled product. The cover web can be fed by the main machine, or can be the product of another and separate press.

20 The details of the invention herein described may be greatly varied by a skilled mechanic without departing from the scope of my invention as expressed in the claims.

Having thus fully described this invention, what I do claim is:—

1. The combination with an assembling mechanism, of a stapling mechanism, means for feeding the assembled product past the 30 stapling mechanism, and a carriage upon which the stapling mechanism is mounted, said carriage having a rack, and a continuously rotating shaft having means for reciprocating said rack and carriage parallel to the line of motion of said product.

35 2. The combination with an assembling mechanism, of a stapling mechanism com-

prising a reciprocable carriage, a shaft journaled thereon, an arm fulcrumed on said shaft, a staple reservoir carried by said arm, and means whereby when the carriage moves 40 with the assembled product, the stapling mechanism will be actuated.

3. The combination with an assembling mechanism, of a stapling mechanism comprising a reciprocable member, a shaft journaled thereon, an arm fulcrumed on the shaft, a staple reservoir carried by the arm, a second shaft journaled on the arm, means carried by the second shaft for driving the staples, means for actuating said arm and 45 staple driving means when the stapling mechanism reaches a certain point, and means for feeding the assembled product by the stapling mechanism and parallel with the direction of motion thereof. 50

4. The combination with an assembling mechanism, of a stapling mechanism comprising a staple reservoir and means for driving the staples, means for feeding the assembled product past the stapling mechanism in a straight line, a carriage upon 60 which the stapling mechanism is mounted, and means for reciprocating said carriage in a straight line parallel to the line of motion of said product. 65

In testimony whereof I have hereunto set my hand, in the presence of two subscribing witnesses.

H. A. WISE WOOD.
